UNITED STATES PATENT OFFICE.

MARCELINO LUQUE NESTAL, OF NEW YORK, N. Y.

REFRIGERATING MACHINE.

Application filed December 11, 1924. Serial No. 755,267.

To all whom it may concern:

Be it known that I, MARCELINO LUQUE NESTAL, a subject of the King of Spain, residing at New York, in the county of New York and State of New York, have invented certain new and useful Improvements in Refrigerating Machines, of which the following is a specification.

This invention is directed to an improvement in refrigerating machines, wherein the material to be cooled or frozen is subjected to a reduction of pressure and to an increase vaporization incident to absorbing the moisture from above the treated liquid.

The invention includes a vacuum pump or like pressure reducer, which is connected with the treated liquid container to reduce the pressure on such liquid, an intermediate container being provided for the reception of a substance having an affinity for moisture, so as to absorb the moisture drawn from the surface of the treated liquid, to thereby increase the vaporization of such treated liquid and thus yield its contained heat more quickly.

The invention is illustrated in the accompanying drawing, in which:

Fig. 1 is a view in section, partly in elevation, of the improved refrigerating machine.

Fig. 2 is an elevation of the pump operator.

Fig. 3 is an elevation of the eccentric for operating the vibrating means.

Fig. 4 is a perspective view showing the parts inclosed in the case-like receptacle, and the latter closed for transportation.

Fig. 5 is a perspective view showing the parts arranged for the refrigeration of an edible material, such for example, as ice cream.

Fig. 6 is a similar view showing the parts arranged for operation with a container adapted for the cooling of water or the like.

Fig. 7 is a view in elevation of a container adapted particularly for ice cream material.

Fig. 8 is a view in section of a container for cooling bottle goods, a bottle in sealed condition being shown within the container.

The improved refrigerating machine, while designed particularly for making ice cream, is also adapted for cooling water, and is equally effective in cooling bottle goods in their original packages. The differences in structure leading to these different results are mainly one of different

structural formations of the containers to be used.

The improved refrigerating machine comprises a case-like receptacle 1, the bottom wall 2 of which provides a base for the support of the apparatus. Near one end a suction or vacuum pump is mounted, including a casing 3, within which is arranged a pump cylinder 4. A hollow piston 5 operates in the cylinder 4, the bottom wall of the piston being formed with an inlet opening 6, normally closed by an upwardly-opening valve 7. A hollow valve stem 8 is connected with the upper wall of the piston, and communicates with the interior of the hollow piston, the hollow stem opening at 9 to the casing beyond the pump cylinder. Secured to the pump cylinder 4 is an auxiliary cylinder 10, a port 11 establishing communication between the cylinders. The upper end of the auxiliary cylinder is threaded to receive the threaded lower end of a pipe connection 12, and threaded within the lower end of the pipe connection is a nipple 13, having an interior valve seat 14, below which the wall of the nipple is formed with outlets 15. A valve 16 for the seat 14 is arranged on the upper end of a stem 17, guided through the lower end of the nipple and terminally provided with an enlarged pressure disk 18.

Obviously on upward stroke of the piston air is drawn through the pipe connection 12, past the valve seat 14, the valve having dropped past the openings 15, out the outlets 15, through the port 11 and into the pump cylinder. Then on the downward stroke of the piston, the air accumulated in the pump cylinder is forced past the valve 6 and out through the hollow stem 8. In this downward movement of the piston, the valve 16 is forced to its seat 14 by the pressure on the disk 18, thus sealing the pipe connection 12 against back pressure.

A container 19 is arranged in the receptacle 1 for a limited vibratory movement, being supported on a movable base 20, with the container pivotally supported in uprights 21 rising from the base 2. A bar 22 is connected to the movable base 20, and in turn connected to one end of an angle lever 23 pivotally supported on an upright rising from the base 2. The lever is operated in a manner to be later described, though it is obvious that operation of the lever will impart a vibratory movement to

the container 19. Carried by the movable base 20 is a bracket 24 providing a support for the container for the treated liquid, it being apparent that the bracket, and therefore the container thereon, is vibrated as and with the container 19.

A container 25 is secured on the bracket 24, and is connected through a tube 26, with the container, the tube in the container 19 leading down to near the surface of a moisture absorbing material, as sulphuric acid, therein. The upper end of the container 19 is connected with a tube 27 to the pipe connection 12 in the pump casing. The connections at the various junctions of the tubes and container extensions are preferably rubber sleeves 28 to assist in maintaining a tight connection without regard to internal pressure.

20 A power shaft 29 is mounted in the upper end of the receptacle 1, and is provided beyond the case with a flywheel disk having a handle 30, whereby rapid movement may be imparted to the shaft. The inner end 25 of the shaft is provided with a disk 31, with a crank connection 32 to the hollow piston stem 8. Immediately beyond the pump casing 3, the shaft is provided with an eccentric 33, the strap of which is connected 30 by a rod 34 with the angle lever 23.

Means are provided for admitting air and oil to the interior of the pump cylinder, to maintain an effective sealing of the piston, and secure proper lubrication of the parts.

35 A casing 35 is mounted on top of the pump cylinder, and has a valved passage 36, opening into the pump cylinder within the limits of movement of the piston. The oil casing 35 is open to the casing 3 above the pump cylinder, through openings 37, and a rod 38 extends through the oil casing and has a valve 39 for closing the passage 36. A spring 40 arranged within the oil casing tends to keep the valve in closed position,

40 a cam 41 on the power shaft 29, operating at each half revolution of such shaft to raise a ring secured on rod 38, tends to raise the valve 39 at each half stroke of the pump piston to admit oil and air to the interior of the pump cylinder.

45 The piston stem opening in the upper end of the pump cylinder is larger than the stem, as at 42, and a disk washer 43, held down by a spring 44 encircling the piston stem and bearing at its upper end against a washer engaging the lower end of the upper guide 45 for the step. At each up-stroke of the piston the disc washer 43 is forced from its seat, and the excess oil is returned to the casing 3 above the pump cylinder.

50 With the material to be treated placed in the container 25, the pump is operated, tending to reduce the pressure on the surface of the treated material. This rapidly withdraws the inherent heat, and cools the ma-

terial. The body of vapor immediately above such material is more rapidly drawn off with the air by the use of the moisture-absorbent material in the container 19, as by the use of such the moisture is absorbed 70 from the air withdrawn by the vacuum pump, and the moisture above the treated material is more rapidly withdrawn, and thus the latent heat of the material dissipated. 75

Obviously water may be cooled or frozen, ice cream or other food stuffs brought to a state of being congealed, or bottle contained liquids reduced in temperature in a rapid and simple manner, all that is required 80 is the introduction of a sufficient quantity of sulphuric acid or the like in the container 19, and the operation of the power shaft.

The temperature reduction is obviously secured in a more rapid manner as a result 85 of the vibration or agitation of the treated material and acid containers. The treated material is thus more readily open to pressure reduction, and the agitation of the moisture absorbent increases its capacity for 90 moisture. Thus the detail of agitation is an important one.

The container 25 is here shown as adapted primarily for the cooling or refrigeration of a contained liquid as water or the like. In the use of the machine for making ice cream for example, a special type of container is preferred. This container, illustrated particularly in Fig. 7, comprises a base portion 46 and a neck portion 47, adapted for a sealing interfit at 48. The body portion 46 is slightly conical with a wide mouth, while the neck portion is reduced for the connection thereto of the tube 26. With the material in the body 46 brought to a proper congealed consistency, the removal of the neck portion 47 permits the ice cream to be dispensed directly from the body portion in a convenient manner. In the use of the device for cooling bottle 100 goods in their original packages, the container comprises a body portion 49 of conical form with a widened mouth, and a neck portion 50 adapted for sealing engagement at 51 with the body portion. The neck portion has an upstanding hollow projection 52 to accommodate the length of the bottles placed therein, and is formed at one side with an opening 53, for the connection thereto of the tube 26. The bottles to be cooled, 105 indicated at 54, are placed in this container and water is placed in the body 49 surrounding the bottle.

An important feature of the invention is the mounting of the entire apparatus in the case-like receptacle 1, to provide for convenient storage and transportation. When not in use, the bracket 24 is removed from the movable base 20, the fly wheel and handle 30 removed from the end of the 110

power shaft 29, and these separated parts placed in the case and the hinged side wall of the latter closed. The entire apparatus may be then conveniently handled through 5 the medium of a handle 56 on the case.

When in use, the only exposed portion is the container mounted on the bracket 24, as will be apparent from Figs. 5 and 6 of the drawings.

19 While the above description presents a preferred embodiment of the invention, it is to be understood that changes in details may be resorted to without departing from the spirit of my invention, and that 15 I regard all such changes that may fall within the scope of the appended claims as included within my invention.

Having thus described my invention, what I claim as new, is:—

20 1. A refrigerating machine, comprising a case-like receptacle, a base arranged therein, a vacuum pump carried by the base, an operating shaft for the pump extending through and beyond one wall of the case, a 25 container base arranged in the case, a lever connection extending from the container base, means operated by the shaft for operating the lever, a container on the container base, a bracket secured to the container base and extending through and

beyond one wall of the receptacle to provide for the reception of a material receptacle, a pipe connection between the air pump and container, and a pipe connection leading from the container for cooperation 35 with a material receptacle.

2. A refrigerating machine comprising a case including a body and a cover therefor, a vacuum pump and an acid container base mounted within the body, means for supporting the acid container base for movement, an operating shaft extending through one wall of the body and connected to the vacuum pump and to the means for operating the acid container base, a material container bracket secured to the acid container base and projecting through and beyond one wall of the body of the case, whereby the material container bracket is operated in and by the movement of the acid container base, and removable pipe connections between the vacuum pump and acid container and the acid container and the material container, the cover for the case inclosing all parts with the exception of the extended end of 45 the operating shaft and the material container bracket.

50 In testimony whereof I affix my signature.

MARCELINO L. NESTAL.
